Primary Examiner—Ralf T. Seifert[57] **CLAIM**

The ornamental design for a yarn cabinet, as shown and described.

DESCRIPTION

FIG. 1 is a front elevational view of the yarn cabinet showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is front elevational view thereof with the doors open showing the interior.

The broken line showing of indicia, in FIG. 1, is for illustrative purposes only and forms no part of the claimed design.
